UNITED STATES PATENT OFFICE.

GEORGE WILLIAM HOWELL, OF LOS ANGELES, CALIFORNIA.

ROCK-DRILL OR IMPACT ENGINE.

1,348,280.

Specification of Letters Patent. Patented Aug. 3, 1920.

Substitute for application Serial No. 45,621, filed August 15, 1915. This application filed February 11, 1920. Serial No. 357,916.

To all whom it may concern:

Be it known that I, GEORGE W. HOWELL, a citizen of the United States, residing at Los Angeles, in the county of Los Angeles, State 5 of California, have invented new and useful Improvements in Rock-Drill or Impact Engines, of which the following is a specification.

This invention relates particularly to 10 engines for rock drills; and although there are many objects and corresponding accomplishments of my invention and embodied in my mechanism, yet the primary object may be said to be the attainment of a maximum 15 efficiency, and with a maximum simplicity of engine mechanism.

In my mechanism there are two members moved (preferably reciprocated) by fluid pressure; these two reciprocating members 20 being a piston or hammer and a valve. My engine operates upon the principle of expanding an initial fluid pressure charge (the charge which initially moves one of the members in one direction) to move that member back in the opposite direction, without requiring any additional charge for the return movement. I am aware that engines of this general nature have been heretofore proposed; but my invention consists of certain 25 mechanisms and certain modes of operation whereby the above stated general mode of operation is made practicable and the efficiency of the engine raised to the highest point. There are several features that I particularly 30 explain hereafter; I may here mention that the single initial charge of air is expanded, step by step, to do all of the work in the machine. No extra charge is used for any purpose. And I attain great 35 efficiency by thus utilizing the expansive power of the fluid; and by eliminating any losses between expansions. The result is that my engine operates upon less energy than any of which I am aware.

Reference is had to the accompanying drawings, in which, for the purpose of this specification, I have illustrated a preferred form of my engine. In said drawings, Figure 1 is a longitudinal section of the engine 40 mechanism; Fig. 2 is a section taken on line 50 2-2 on Fig. 1; Fig. 3 is a longitudinal sec-

tion showing the movable parts in positions opposite those shown in Fig. 1; and Fig. 4 is a section taken on line 4-4 of Fig. 3.

The numeral 10 designates a cylindrical 55 casing having two bores 11 and 12 of different diameters. In this double-bored cylinder I fit a piston or hammer 9 which has a large head end 13 and a smaller rear end 14; and this piston or hammer is preferably 60 made solidly of a single piece so that it becomes an effective hammer to strike a blow, upon each reciprocation, on any suitable member 15 at the forward end of the cylinder.

Two ports 16 and 17 lead into the rear 65 small end 11 of the cylinder, the port 16 entering the extreme rear end against the head 18, and the port 17 entering forward of the port 16 but somewhat behind the foremost position of the rear end of the hammer. At 70 the extreme forward end of the large cylinder bore 12 there is a port 20; and a port 21 also is placed just forward of the rearmost position of the forward end of the hammer. This port 21 I may term the initial exhaust 75 port; and it has a peculiar function in causing the movement of the controlling valve, as hereinafter described.

The rear end of the cylindrical casing is enlarged, as at 10^a, to hold a stationary valve 80 sleeve 30 which has a small bore 31 at its rear end and a large bore 32 at its forward end. A valve 33 reciprocates in this valve sleeve 30, having a large head end 34 and a smaller rear end 35; and a longitudinal passage 36 85 extends rearwardly from the head end face of the valve to a point near the rear end where it connects with the ports 37. When the valve is in the position shown in Fig. 1 the valve 33 register with a port 38 through 90 the valve sleeve 30, which port 38 registers permanently with the port 16. When the valve 33 is in its rearmost position the ports register as shown in Fig. 1; while, when the valve is in its forward position, the rear 95 end of the small part of the valve passes the port 38 and leaves this port open for direct entry of air or other fluid pressure from the intake port 39 through the bore 31 and ports 38 and 16 to the rear end of the smaller cylinder bore 11 to press the hammer forwardly 100 toward the position shown in Fig. 3. It is

one of the features of my invention that the ports between the valve and the various parts of the cylinder are short and direct; so that the action is quick, positive and efficient, no appreciable time of volume of air being lost during passage of the air through long ports or passage ways.

The port 20 is connected by a passage 40 with a port 41 in the valve sleeve, which port 41 is just forward of the head end of the valve when the valve is in its rearmost position as shown in Fig. 1, and just behind the head end of the valve when the valve is in its forward position as shown in Figs. 3 and 4. Port 21 is connected by a passage 42 with a port 43 through the valve sleeve at the rear end of the large forward bore 32 of that sleeve; so that this port 43 never communicates with the space ahead of the large end 34 of the valve. Port 41 communicates with port 43 when the valve is forward and this communication is stopped when the valve is rearward. The port 43 and the port 21 both communicate with atmosphere through the passage 44 which connects with the passage 42 and leads, through the valve 45, to atmosphere at 46. The valve 45 is provided to partially or wholly choke the exhaust to atmosphere; but, during full operation, this valve 45 is left wide open for free exhaust.

Having now explained the broader features of the mechanism embodying my invention, I proceed to the statement of the operation of that mechanism and of certain preferred details of construction. Suppose that the parts are shown in Fig. 1 and that fluid pressure is applied through the passage 39. This fluid pressure upon the rear end of the valve immediately presses the valve 23 forwardly to the position of Fig. 3. Fluid pressure immediately enters through the ports 38 and 16 and causes the immediate forward movement of the hammer toward the position shown in Fig. 3. During this forward movement, before it reaches its foremost position, the rear end of the hammer uncovers the port 17 and allows the full pressure from the cylinder 11 to pass through the port 17 and to exert itself upon the forward large face of the valve; and when this occurs the valve moves back to its rearmost position shown in Fig. 1, due to excess of pressure on its forward face over that on its rear face. The hammer continues to move forwardly by its momentum and expansion of the pressure fluid behind it, striking its blow upon the member 15. The drawings show the proportionate distance which the hammer will travel and deliver an effective blow, after uncovering port 17.

When the valve moves back to its original position, shown in Fig. 1, the port 17 is immediately connected with the port 41 ahead of the front large end of the valve, so that the pressure from the small cylinder

bore 11 then passes immediately through the ports 17 and 41, the passage 40 and port 20 to the front end of the large cylinder bore 12. At the same time the valve ports 37 register with the port 38 and air pressure from the small cylinder bore 11 passes also through the port 16, the valve passage 36, the ports 41, passage 40 and port 20 to the forward end of the large cylinder bore. When the valve moves rearwardly the initial pressure is cut off. Consequently, the charge of fluid under pressure originally introduced into the small cylinder bore 11 is expanded through the passage 40 and port 20 into the forward large cylinder bore 12 ahead of the 80 large end 13 of the hammer. The ports and passages being large and direct in their connection, the pressures behind and ahead of the hammer equalize; and, the total pressure on the head end of the hammer being 85 greater than that on the rear end, the hammer will be moved back to the position shown in Fig. 1 by this difference of pressures; the fluid constantly expanding to fill the larger bore 12 and being constantly 90 pressed out of the smaller bore 11 by the rearward motion of the hammer. It will be remembered that the initial pressure through port 39 is still pressing forwardly on the small rear end of the valve; and, simultaneously, the reduced pressure of the expanded charge of fluid is pressing rearwardly upon the large forward face of the valve. The area of the head end of the valve is such that this reduced pressure acting 100 upon its surface will still hold the valve back against the initial pressure at its small rear end; but also such that a comparatively small reduction of the reduced pressure at the head end will cause the immediate forward motion of the valve under the pressure at its rear end.

The hammer moves rearwardly under the influence described, and when it nears its rearmost position it uncovers the initial exhaust port 21, allowing a part of the air in the large bore 12 to pass directly to atmosphere. This action reduces the pressure in the large bore 12 and thereby reduces the pressure upon the forward large end of the 115 valve; and the valve is immediately pressed forward by the initial air pressure against its small rear end. When the valve moves forwardly to the position shown in Fig. 3, initial pressure again enters the small rear bore 11 of the cylinder, and moves the plunger forward again, in the same manner as before described. During this forward movement the port 21 is connected with the port 43 behind the head 34 of the valve; so 120 that the pressure in the large bore 12 is exhausted directly through the port 20, passage 40, port 41, valve bore 32, port 43 and passage 44. Choking of the exhaust not only diminishes the force of the blows but 130

slows the hammer reciprocation; for the reason that restriction of the exhaust through the port 20 causes a cushion of fluid to remain ahead of the hammer and that restriction of the preliminary exhaust retards that reduction in pressure which causes the forward movement of the valve. This cushion effect may be also attained by changing the position of port 17; by moving it farther to the right in Fig. 1 the valve motion to the right will take place earlier with respect to the piston stroke and the expanding fluid will pass through port 20 into cylinder 12 ahead of the piston before it reaches the end of its stroke forward.

Not only does the initial charge of air expand to move the piston or hammer back to its initial position, but also this initial charge of air operates the valve itself; and, throughout the cycle of operations, the initial charge of air is expanded step by step, doing a certain and definite piece of work upon each expansion. I shall now illustrate with specific figures taken from a full sized operating engine. The area of the rear small end of the hammer is 1.767 square inches; and at an initial pressure of, say, one hundred pounds per square inch the pressure exerted on the rear end of the hammer on its forward travel will be practically 176.7 pounds. (In giving these figures I ignore the fall of pressure due to passage through ports; and due to flow of the fluid.) The initial pressure follows the piston to the end of its travel, and, when the port 17 is uncovered, enters this port and presses against the large forward end of the valve. This end has an area of 0.601 square inches; and the rearward fluid pressure is therefore 60.1 pounds. The area of the small rear end of the valve 0.196 square inches and the initial pressure against that end is therefore 19.6. The excess pressure from the forward end presses the valve back to the position shown in Fig. 1. Immediately the connection of the cylinder 11 to the air supply is cut off the air charge is expanded through the port 40 into the forward end of the large cylinder bore 12. At the instant of commencement of piston movement to the right in Fig. 1, the initial charge of air has been expanded to occupy a space represented by the cylinder 11, the valve bore 32, and the passage 40. The initial charge has a volume equal to the volume of the cylinder 11 (the piston stroke being 3.5 inches) plus the volume of the space 32 ahead of the valve, which totals 6.635 cubic inches. Upon expanding to fill the volume of the port 40, which is just one cubic inch, the total volume is then 7.335 cubic inches and the pressure becomes about eighty-seven pounds. The area on the front large end of the hammer is 2.761 square inches; and the total pressure at eighty-seven pounds per square inch is

therefore two hundred forty pounds. Simultaneously, at the same pressure per square inch, the total pressure against the rear small end of the hammer is 153.5 pounds; and the excess pressure is therefore 86.5 pounds tending to move the hammer rearwardly. When the hammer has moved entirely to the rear, then the space occupied by the charge of air is approximately the valve bore 32, the port 40 and the full cylinder 12, which totals 11.1 cubic inches; and the pressure becomes about 59.7 pounds per square inch. The pressure then upon the forward large face of the piston is about 165 pounds, and the pressure on the small rear face is 105.3 pounds; and the difference or effective pressure tending to press the piston rearwardly is 59.7 pounds. It will be noted that the pressure is now reduced to 59.7 pounds per square inch; and the pressure, consequently, upon the large end of the valve becomes 35.9 pounds, which is still greatly in excess of the pressure of 19.64 pounds at the small rear end; but the excess is not so great but that a comparatively small exhaust of fluid from the cylinder 12 will reduce this pressure to a point below the pressure at the rear end, allowing the valve to be moved forwardly. The exhaust port 21 is so designed that, during the time the piston uncovers this port, a sufficient exhaust will take place to reduce the total pressure on the front end of the valve to less than 19.64 pounds. The valve is small and comparatively light; and a very small excess pressure at its rear end will move it very quickly. It is desirable to have the valve move quickly; and on the other hand it is desirable not to require too great a reduction of pressure on the front end of the valve, as this would require a longer time period for said reduction. And, consequently, it is desirable to bring the expanded fluid pressure down fairly low before effecting this said reduction, so that the reduction can be made quickly through a port of practical size. On the other hand, the head end of the valve is made sufficiently large so that, while the reduced pressure of 35.9 pounds is upon it, there is no liability of any premature action of the valve. This excess of area and pressure also provides for loss of pressure through the machine by reason of restriction of flow or leakage or any other cause. And on this point it may be well to state that, owing to this particular feature of my device, it is not necessary that the different parts be excessively tight. A slight leakage by the piston or valve will not cause the machine to be inoperative in any way.

Having described a preferred form of my invention, I claim:

1. In an engine mechanism, the combination of a suitable casing having a cylinder with relatively large and small bores and a

- valve chamber with relatively large and small bores, a reciprocating piston in the cylinder with large and small ends, a reciprocating valve in the valve chamber with 5 large and small ends; means to conduct an initial fluid pressure to the small valve bore to press against the small end of the valve and move it forwardly, means opened by the valve when so moved to admit the initial 10 fluid pressure to the small cylinder bore to press against the small end of the piston and move it forwardly, means opened by the piston in its forward movement to admit the fluid pressure from the said cylinder bore to 15 the large valve bore to press against the large end of the valve to move it rearwardly to close off the supply of initial fluid pressure to the small cylinder bore, means opened by the valve when moved rearwardly to admit the fluid pressure from the small cylinder bore and from the large valve bore into the large cylinder bore to press against the large end of the piston and move it rearwardly, said last mentioned means including 20 a port leading from the large valve bore to the large cylinder bore, means opened by the piston at the rear end of its movement to directly exhaust pressure from the large cylinder bore and thereby through the communication of the last mentioned port to 25 exhaust pressure from the large valve bore to reduce pressure on the large end of the valve so that the initial pressure at its other end will then move it forwardly, and means including an exhaust port leading from the large valve bore and adapted to be connected with the said last mentioned port when the valve moves forwardly.
2. An engine mechanism, embodying a cylinder having tandem bores of relatively large and small diameters, a reciprocating piston with relatively large and small parts fitting said bores, there also being a valve chamber having relatively large and small 40 tandem bores, a reciprocating valve therein having relatively large and small ends, there being an initial pressure inlet port leading to the small valve bore, a port leading from the small valve bore at a point coverable by 45 the small end of the valve to the end of the small cylinder bore, a port leading from the small cylinder bore at a point somewhat removed from its end to the end of the large valve bore, a port leading from an intermediate point in the large valve bore to the 50 end of the large cylinder bore, an exhaust port leading from the large valve bore behind the large end of the valve to atmosphere, and an exhaust port leading from an intermediate point in the large cylinder bore to atmosphere, the volumes and dimensions of the parts being such that when the charge 55 that is initially taken into the small cylinder bore is expanded to fill the large cylinder bore then the pressure upon the large

end of the valve is greater than the initial pressure on its small end.

3. A rock drill or impact mechanism of the character set forth, embodying a cylinder having bores of relatively small and 70 large diameters, a piston with small and large parts fitting said bores, there being also a valve cylinder with bores of relatively small and large diameters; a valve with relatively small and large parts fitting in said 75 bores, an initial pressure port on the small end of the valve, an initial inlet port between the small valve bore and the small cylinder bore, a port between the small cylinder bore and the large valve bore adapted to be uncovered by the small end of the piston to admit pressure from the small cylinder bore to the large valve bore to act against the large end of the valve, an exhaust port leading from the large valve bore behind the 80 large end of the valve to atmosphere, an exhaust port leading between the end of the large cylinder bore and the large valve bore intermediate the port which admits pressure from the cylinder to the valve bore and 85 the exhaust port, so that reciprocation of the valve will alternately connect the last named exhaust port alternately with said two ports, and an auxiliary exhaust port to atmosphere leading from the large cylinder 90 bore at a point to be uncovered by the large end of the piston at or near the end of its stroke, the valve having a longitudinal passage leading from its large end through the valve to a point near the small end of the 95 valve adapted to register with the initial pressure port when the valve is moved against the initial pressure.

4. An engine mechanism, embodying a cylinder having tandem bores of relatively 105 large and small diameters, a reciprocating piston with relatively large and small ends fitting said bores, there also being a valve chamber having tandem bores of relatively 110 large and small diameters, a reciprocating valve having relatively large and small parts fitting said bores, there being an initial inlet port to the end of the small valve bore to constantly apply pressure to the small end of the valve, a port leading from the small valve bore at a point coverable by the small end of the valve to the end of the small cylinder bore, a port leading from the small cylinder bore at a point somewhat removed from its end to the end of the large valve 115 bore, an exhaust port leading from the back end of the large valve bore behind the large end of the valve, an exhaust port leading from the large cylinder bore at a point somewhat removed from its end and to be uncovered by the large end of the piston, and a port leading from the end of the large 120 cylinder bore to the large valve bore at a point midway between the two other said ports leading to said large valve bore, the 125

arrangement of said ports being such that the reciprocation of the valve causes the last stated port to alternately communicate with the two other ports, and said valve having 5 a longitudinal port therethrough leading from its large end to a point near its small end there communicating with transverse ports registerable with the port which leads

from the small valve bore to the small cylinder bore.

In witness that I claim the foregoing I have hereunto subscribed my name this 3d day of February, 1920.

GEORGE WILLIAM HOWELL.

Witness:

VIRGINIA I. BERINGER.
